HOLDER FOR TRASH RECEPTACLE

Hoke S. Barrett, Kinchafoonee Creek Road, Rte. 2,
Leesburg, Ga. 31763

Filed Oct. 3, 1968, Ser. No. 13,831

Term of patent 14 years

Int. Cl. D7—06

U.S. Cl. D49—30

Fig. 1

Fig. 2

Fig. 3

Fig. 4

Fig. 5

Fig. 6

FIGURE 1 is a top plan view of a holder for trash receptacle, showing my new design.

FIGURE 2 is a bottom plan view thereof.

FIGURE 3 is a side elevational view thereof, all four sides being the same.

FIGURE 4 is a perspective view thereof.

FIGURE 5 is a front elevation of a modified embodiment of the holder shown in FIG. 1, the rear being the same as the front and the opposite undisclosed end portions are the same as that shown in FIG. 3.

FIGURE 6 is a top plan view of the modification shown in FIGURE 5.

I claim:

The ornamental design for a holder for trash receptacle, as shown and described.
